Primary Examiner — Kevin K Rudzinski*Assistant Examiner* — Paul D Bohannon(74) Attorney, Agent, or Firm — Eric Karich; Karich & Associates(57) CLAIM

The ornamental design for a gaming chair bean bag, as shown and described.

DESCRIPTION

FIG. 1 is a perspective view of a gaming chair bean bag, showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of a zipper is for the purpose of illustrating portions of the gaming chair bean bag that form no part of the claimed design.

1 Claim, 7 Drawing Sheets(56)
